M. NOETH.
HEATING STOVE.
APPLICATION FILED NOV. 8, 1918.

Patented June 28, 1921.

2 SHEETS—SHEET 2.

Michael Woeth Inventor
Offield Towle Graves & Sons Attorneys

UNITED STATES PATENT OFFICE.

MICHAEL NOETH, OF CHICAGO, ILLINOIS.

HEATING-STOVE.

1,382,667.

Specification of Letters Patent. Patented June 28, 1921.

Application filed November 8, 1918. Serial No. 261,600.

To all whom it may concern:

Be it known that I, MICHAEL NOETH, a citizen of the United States, residing at Chicago, in the county of Cook and State of Illinois, have invented certain new and useful Improvements in Heating-Stoves, of which the following is a specification.

My invention relates to new and useful improvements in heating stoves and has for its salient objects, to provide an extremely simple and efficient heating stove so organized as to burn the fuel, particularly soft coal, very perfectly and therefore with the production of a minimum amount of smoke; to provide a construction and arrangement in which the initial combustion takes place in a relatively large and high combustion chamber in direct and unrestricted communication with the upper part of the fire pot, whereby free combustion is promoted; to provide a construction and arrangement in which ample supplies of air are admitted to the lower part of the mass of fuel and to the upper part of said mass, the upper supply being fed in through a heated conduit so as to meet the burning gases in pre-heated condition; to provide a construction and arrangement in which return or up and down combustion passages are provided entirely contained within the main drum or outer wall of the stove; to provide a construction and arrangement in which these return passages may be functionally cut out and the stove used as a direct draft stove by the simple shifting of a damper; to provide a construction and arrangement in which unusually free and ready access may be had for feeding in the fuel and for stoking it, notwithstanding the presence of the return passages referred to; to provide a construction and arrangement in which certain elements which aid in making the return passages may be readily removed and the return passages thoroughly cleaned from soot and ashes; to provide a construction in which the air inlet conduit may be readily removed for cleaning, and in general to provide a simple and improved construction of the character referred to.

50 The invention will be readily understood from the following description, reference being had to the accompanying drawings, in which:

Figure 1 is an axial vertical sectional view

taken in a plane extending from front to rear of the stove.

Fig. 2 is a horizontal sectional view taken on line 2-2 of Fig. 1 and looking downwardly.

Fig. 3 is another horizontal sectional view taken on the line 3-3 of Fig. 1 and looking downwardly.

Figs. 4 and 5 are fragmentary details of the air inlet conduit and its support.

Fig. 6 is a perspective view of the partition arrangements of the interior of the stove, looking into the rear half of the stove.

Fig. 7 is a perspective view of the half disk damper mounted in the upper part of the stove and controlling the return draft passages.

Figs. 8, 9 and 10 are perspective views of the several parts of the partitions which aid in forming the return draft passages.

The preferred embodiment of my invention which I have shown is adapted to the burning of soft coal; the base part 1 of the stove is preferably of cast metal, constructed to provide a closed ash pit 2, and below the grate 3, and into which ash pit air is admitted through a suitable damper door 4. The upper periphery of the base is rabbeted as indicated at 5, to receive a bowl shaped cast section 6, which constitutes the fire pot of the stove. The grate 3 is supported at the bottom of this bowl, as clearly shown in the drawings. The drum 7 or main outer side wall of the stove is preferably of sheet metal and mounted at its lower end upon the periphery of the bowl member 6, also as clearly shown. The upper end of the drum is closed by a suitable top 8, which is provided with a flanged smoke outlet 9, upon which fits the first section of stove pipe 10. Within the lower end of the drum and rising upon the upper edge of the bowl 6, there is a ring 11, which is interrupted at the front of the stove to receive a main fitted door 12, which is inset through the drum and at its lower edge mounted upon the bowl 6. The door 12 will ordinarily be provided with a damper control inlet as indicated at 13.

The intermediate part of the interior of the drum is divided by a vertical partition into front and rear halves and said rear half is again subdivided by a vertical partition into two passages. To this end, a horizontal

half disk partition 14 is mounted upon the upper edge of the ring 11, and in order that this partition 14 may be readily removable, it is made of two 90° segments, as shown clearly in Fig. 10. The front edges of these segments are provided with upstanding flanges 15.

The numeral 16 designates the transverse vertical partition which divides the intermediate part of the drum into front and rear compartments. This member 16 fits at its edges in grooved strips 17, applied to the inner wall of the drum, while at its lower edge it is detachably connected to the upstanding flanges of the member 14.

19 designates the partition member which divides the rear half of the drum into two compartments or passageways. This member 19 is supported at its edges in guides 20, 21, applied to the face of the partition 16 and interior of the drum 7 respectively. One of the two segmental shaped return passages 22 and 23 is closed at its upper end by a segment shaped partition 24, but 25 the other passage 23 is in free and open communication with the upper interior of the drum. In order to place the front combustion space of the stove in communication with these return passages and the return passages 30 in communication with each other, a port or opening 25 (see Fig. 6) is formed through the upper part of the partition member 16, and another port 26 is formed through the lower part of the partition member 19. The lower port 26 is formed in the present instance by simply shortening the partition member 19.

In order to change the stove from direct draft into an indirect draft, or vice versa, 40 a half disk damper plate 27 is mounted in the upper part of the drum upon a pivot 28, and controlled by a rack and pinion so that it may be shifted into either direct or indirect positions. As shown, the pivot 28 is 45 carried by a pair of brackets 29 and 30 mounted upon the drum and extending to the center thereof, where they overlap. The bracket 29 is extended beyond the pivot 28, as indicated at 31, and turned down 50 to form a guide for the rack bar 32. The pinion 33 is fast upon the damper plate, as best seen in Fig. 7. It will be obvious that when the damper plate 24 is in position to overlie the rear half of the drum and the 55 return passages therein, there will be direct communication between the fire box and the outlet of the stove, while upon turning the damper plate one-half around, the direct draft will be completely cut off and an in- 60 direct or return draft circulation established, as follows:

The gases of combustion arising from the fuel in the fire-pot will flow upwardly through the front half of the drum, thence 65 rearwardly through the port 25 into down-

take passages 22, thence through port 26 into uptake passages 23 and out through the open upper end of the latter into the upper space of the drum and through outlet of the latter. Of course, by shifting the damper plate 24 only partly, the circulation will be partly direct draft and partly return draft.

An important feature of my invention resides in the provision of a regulable amount of preheated air discharged into the fire pot just above the fuel therein. At this end I provide a conduit pipe 34 which preferably extends inwardly from the rear side of the drum just below the partition member 14, as seen clearly in Fig. 1. The inner end of the pipe is conveniently supported by wire loop 35 (see detail Fig. 5) mounted upon the pair of bolts 36, which serve to hold the partition members 14 to the upright partition member 16. The inner end of said pipe is capped and upon its outer end is mounted a damper body 37, the inlet of which is controlled by rotatable damper 38. The under wall of the pipe 34 adjacent the inner end is provided with a plurality of perforations 39 for directing the air supplied through the pipe 34 downwardly into the fire box, the admission of air being due to the draft through the stove and out the flue 10, which serves to draw in air through the pipe 34 and deliver it downwardly toward the burning fuel in the fire box to facilitate combustion. The damper body 37 is threaded upon the end of the conduit pipe as shown. By simply unscrewing the damper body of the pipe and disconnecting loop 35, said pipe may obviously be readily removed from the stove. By taking out bolts 36, the two segments which together formed the horizontal position 14 may also be removed from the stove and any dust or soot collected in the passages above said partition removed.

While I have herein described and illustrated a preferred embodiment of my invention, it will, of course, be understood that the details of construction and arrangement may be somewhat modified without departing from the invention.

I claim as my invention:

1. In a heating stove, the combination of a fire pot, a flue at the upper end of the stove, a combustion chamber between the fire pot and flue, a segmental partition fixed in the bottom of the chamber, a partition at the top of the chamber above a portion of the bottom partition, vertical plates between the partitions, one extending upwardly from the bottom partition terminating short of one edge of the upper partition and another extending downwardly from the other edge of the upper partition terminating short of the bottom partition, and a rotatable segment at the top movable to extend the upper partition in one direc- 130

tion directly over that covered by the lower segment and in the other direction to overlap that portion of the chamber not embraced by the lower segment, to make a 5 direct and indirect draft through the combustion chamber.

2. In a heating stove, a fire pot, a flue at the upper end of the stove, an intermediate combustion chamber, and means in 10 the chamber to form a direct or an indirect gas passage therethrough; said means including partitions forming with the chamber wall a vertical passage open at top and bottom, a second vertical passage closed at 15 the top and open at the bottom, and an intermediate passage closed at top and bottom with an opening in one wall at the bottom of the second passage and another opening in another wall at the top of the 20 first passage; and a rotatable partition movable over the top of the first vertical passage to cause gas to pass through the intermediate passage and over the top of the second vertical passage to open the first 25 passage for direct draft.

3. In a heating stove, a fire pot, a flue at the upper end of the stove, a combustion chamber having partition means forming an open draft passage, a second passage 30 open at the top and closed at the bottom, and an intermediate passage closed at top and bottom but having side ports, one connected with the top of the draft passage and the other with the bottom of the sec- 35 ond passage, a pivoted partition member to swing over the top of the second passage or over the draft passage to cause direct or indirect draft, a pinion secured to the pivoted partition member, and a rack en-

gaging the pinion and extending without 40 the chamber for rotating the partition.

4. In a stove, the combination of an upright casing having a fire box at the lower end and a draft outlet at the upper end, and a door at the side of the casing for 45 supplying fuel to the fire box, a partition extending inwardly from the opposite side of the casing toward the door and overlying substantially one-half of the fire-box, a wall in the casing extending upwardly 50 from the inner edge of said partition and terminating below the draft outlet, so as to divide the interior of the casing between the fire box and draft outlet into two pas- 55 sageways, means extending outwardly from the center of said wall to the wall of the casing so as to divide the passageway above said partition vertically into two parts and a valve at the upper end of the said wall for optionally obstructing or causing circu- 60 lation through the two part passageway from the fire box to the draft outlet of the casing.

5. In a stove, the combination of a cas- 65 ing having a fire box at the lower end and a draft outlet at the upper end, support- ing means extending inwardly from the wall of the casing above the fire box, and a horizontal partition with vertical parti- 70 tions thereabove supported by the said means for dividing the casing above the fire box into a plurality of vertical pas- sageways, and adjustable means for afford- 75 ing circulation directly from the fire box to the draft opening or consecutively through said passageways.

MICHAEL NOETH.
